DRUM WASHING APPARATUS

Stephen Stewart Walde, London, England, assignor to
Victor Blagden & Company Limited, London, Eng-
land, a British company

Application February 10, 1954, Serial No. 409,430

8 Claims. (Cl. 134—46)

This invention comprises improvements in drum washing apparatus for oil drums and like vessels in which a jet is entered from below into the vessel which is to be cleaned through its mouth while the vessel is inverted so that detergent is projected into the vessel through the jet. It is quite common in bottle-washing and like apparatus to direct a stream of detergent into an inverted vessel which is to be cleaned, but to apply a jet near the bottom of an oil drum, is not adequate, because the size of the drum, the sharp internal corners or joints which it contains and the affinity of oil and like substances for the metal of the drum, necessitate a peculiarly thorough washing action which cannot be attained unless a long jet is entered right inside the drum and unless the interior surface of the drum is closely sprayed repeatedly with detergent. To get a nozzle right inside the drum mechanically, it must have a periodic stroke into and out of the drum of considerable length. In order to obtain a thorough washing, especially in the case of oil or chemical drums, it is desirable to flush the vessel out several times with detergent followed by further flushing with wash water. In producing a machine for the purpose, in which vessels on a conveyor pass progressively through the machine, the problem arises of how best to produce this repeated long-stroke washing action without undue complication and also of how best to arrange the progress of the conveyor to fit in with the repeated actions of the detergent nozzles.

With a view to overcoming these and other problems which arise in such apparatus, the present invention contemplates the employment of a conveyor and a step-by-step mechanism for moving the conveyor in conjunction with a movable frame upon which washing nozzles are mounted, guide-means on the conveyor to correlate the positions of the drums to be washed with the nozzles, and operating means for synchronising up and down movements of the nozzles with translatory movements of the conveyor and for centering the parts relatively to one another.

By moving the jets up and down, they do not remain permanently in the vessels which are to be washed while these are on the conveyor, but are withdrawn, which facilitates draining. Neither do the jets have to be mounted on the conveyor and the supply of liquid to the jets is simplified.

Furthermore, the jets can be formed to direct the liquid radially on to the walls of the vessel to be washed as they rise into the vessel; thus the streams of liquid then impinge directly on the internal surfaces of the vessels and the impingement occurs progressively over the whole surface of each vessel as the jet is moved therein, and so increases the efficiency of the cleansing operation. This is particularly important in the case of vessels such as oil drums, which have a large internal area and a small orifice.

In a preferred construction in accordance with the present invention, the jet-carrying structure is mounted

2

for up-and-down movement only, and is driven by a continuously rotatable member connected to an intermittent feed device for the conveyor in such manner that the up-and-down movement of the jet-carrying structure alternates with a forward movement of the conveyor which occurs when the jet-carrying structure is substantially at rest at the bottom of its stroke. In this way the jet-carrying structure has only an up-and-down movement to perform, performing this movement during the major part of the cycle of operation, and the vessels on the conveyor move horizontally relatively to the jets while the jets are at the lower part of their stroke and during a minor portion only of the cycle.

The invention further relates to the provision of means whereby detergent and washing water are kept separate from one another, to safety devices for preventing escape of detergent and of further features which are hereinafter more fully described.

The following is a description by way of example of two constructions in accordance with the invention, reference being made to the accompanying drawings in which:

Figure 1 is a side elevation of one form of apparatus.
Figure 2 is a plan of the same.

Figure 3 is a section upon the line 3—3, of Figure 1, looking in the direction of the arrows.

Figure 4 is a view similar to Figure 1, but of a modified form of apparatus.

Figure 5 is a plan of the same.

Figure 6 is a section upon the line 6—6, of Figure 4 looking in the direction of the arrows, and

Figure 7 is a detail of the driving gear of the construction shown in Figures 4—6.

Figure 8 is a detail of a cradle for oil drums, and is equally applicable to the construction shown in Figures 1, 2, and 3, or to the construction shown in Figures 4 to 7, and

Figure 9 is a further detail showing the entry of a detergent nozzle through a bung-guide into an oil drum, and

Figure 10 is a section through the bung hole of a drum.

Referring first to the construction shown in Figures 1 to 3, this comprises a chain conveyor 11 which runs over pulleys 12, 13, 14 and 15, so that it has an upper horizontal working path 16 and a lower return path 17. The pulleys are supported in bearings on side frames 18, 19. The side frames are made by vertical plates which are stiffened along the top by angle-irons 20, 21, and by vertical ribs, 22, 23 at intervals. The lower ends of the ribs, 22, 23 rest on flanges 24, 25, and the flange 24 is supported on a concrete base 26, which forms one side of a pit 27. The flange 25 rests on the top of a detergent reservoir 28, which is located in the pit. It is also supported at its ends on the concrete.

Between the side frames 18, 19 along their top edge there is secured angle-iron guides 29, 30, which form ledges along which the two side chains 11 run when passing along their upper horizontal working path. The side chains 11 support, and are kept spaced apart by, cradles 31, a construction of which appears in Figures 8 and 9. Each of the cradles 31 consists of two angle-members 32, 33, set parallel to each other with one flange vertical and the other flange extending from the top of the first horizontally towards the other of the two angle-members. The angle-members are united at each end by vertical cross-plates 34, 35, and the cross-plates are drilled to receive bolts 36, which pass through the chain 11 and act as hinge-pins for some of the links. Welded to the outside of each of the angle-irons 32, 33 is an upstanding cradle-plate 37 or 38, as the case may be. The cradle-

plates serve to support the sides of drums 40, which are laid horizontally on the cradle. It is a matter of great importance to locate each drum accurately in relation to the cradle so that the bung-hole of the drum comes into an exact position between the angle-irons 32, 33 where it can be entered in due course by the washing nozzles of the machine.

To this end each cradle carries a bung-locating funnel 41, which is located mouth downwards and stem upwards between the angle-irons 32, 33. The funnel 41 has ears 42, on each side, which are bolted to supporting ears 43, welded to the undersides of the angle-irons 32, 33. The mouth or lower end of the funnel is wide enough to catch and guide a nozzle 44 located on an upstanding stem 45, if the nozzle is advanced upwardly into it from below. The neck 46 of the funnel tapers to a size a little larger than the stem 45, and the diameter of this part of the funnel is substantially smaller than the opening of any normal bung in an oil drum. The neck of the funnel therefore acts as a locating member for the bung of an oil drum which may be rested on the cradle-plates 37, 38, with its bung beneath it and surrounding the neck 46. If a drum is so positioned on the cradle, and the nozzle 44 is pushed upwardly through the funnel, the funnel will guide it so that the nozzle enters the drum through the bung-hole. The manner of lifting and lowering the nozzles 44 is hereinafter explained.

Another angle-member 47, welded to end-plates 48, 49 extends across the chain from side to side near to each of the cradles 31 and the end-plates are bolted by bolts 50 to the conveyor chains, as seen most clearly in Figure 8. The end-plates 48, 49 support the cross-member 47 at a level somewhat higher than the cradle 31, and the cross-member 47 forms a support which is utilised in conjunction with the cradle when drums of the type which have bungs in their end are employed. Again the bung-hole is located by the neck 46 of the funnel 41, and the drum is supported partly on the angle-iron 32, and partly on the cross-member 47, as indicated by the chain line 51 in Figure 9. This holds the drum on its end in a slightly sloping position with the bung in the lowermost place so that any oil which the drum may contain will drain out at the bung-hole. Oil is similarly drained out if present, from the drums 40, and it flows over the outside of the funnel 41. One end of the conveyor constitutes a loading station. Below the loading station an oil collecting tray 52 extends between the side-plates 18, 19 from side to side. The oil collecting tray has its bottom inclined downwards towards the centre, where there is a drain 53 to deliver oil into a sump 54. The tray 52 is long enough to extend under several oil drums as located on the conveyor, and therefore, each drum will remain above the tray for several steps of the conveyor movement, and this will give an opportunity for excess oil to drain out and be collected for recovery and re-use or for fuel or otherwise. The driving mechanism of the conveyor is located towards the other end, and comprises a continuously rotating drive shaft 60, operated at a slow speed by a motor 61, through a reduction gear 62. The shaft 60 carries a locking disc 63 and a Geneva-cross feed mechanism, and secured to each face of the locking disc 63 is an arm 64, which projects beyond the edge of the locking disc. The arms 64 support between them an operating roller 65. On an adjacent parallel shaft 66 is located a Geneva-cross 67, and the roller 65 co-operates with the slots in the cross to move the shaft 66 intermittently through one quarter of a revolution at each revolution of the shaft 60. The shaft 66 is geared by a chain 68, running over sprockets 69, 70 to the shaft which carries the chain sprockets 14 of the conveyor. Thus the conveyor is advanced step by step upon rotation of the shaft 60 and the velocity ratio of the gearing is made such that each quarter revolution of the shaft 66 will move the conveyor forward a step which is equal to the pitch spacing between the drum locating funnel necks 46 on the cradles 31.

The shaft 60 also carries a sprocket 71, which is connected by a chain 72 to a sprocket 73 on a nozzle operating shaft 74. The nozzle operating shaft carries a bevel gear 75, which operates a shaft 76 extending alongside the frame 18, and this in turn through another bevel gear 77, operates a shaft 78. The shafts 74 and 78 rotate in unison with one another and each of them carries cranks 79, which support a crank-pin 80. The crank-pin 80 works in a horizontal slot 81, in a jet-carrying frame 82.

10 The jet-carrying frame is best seen in Figure 1 of the drawing where it is seen in dotted lines, although it is shown in full lines in Figures 2 and 3. The jet-carrying frame may be built up of two channel-members spaced apart back to back, one above another and provided with 15 front and back plates 83, 84, between which there is supported a longitudinal pipe 85. The pipe 85 carries the nozzle stems 45 as most easily seen in Figure 3. It terminates at 86. One end of the pipe 85 is connected by a rubber hose 87 to a fixed supply pipe 88. The supply pipe 88 receives detergent from a centrifugal pump 89, driven by an electric motor 90, and the pump drains from the detergent tank 28.

At the other end of the jet-carrying frame 82, there is a water supply pipe 95 and nozzle 120 which is connected by a rubber pipe 96 to a supply pipe 97 supplied with water by a centrifugal pump 98 driven by electric motor 99.

One end of the detergent reservoir 28, is divided off by a partition 100 to form a wash water sump 101, and 30 the centrifugal pump 98 drains from the sump 101.

Below the main portion of the conveyor from the end of the tray 52, as far as the partition 100, there is a detergent collecting tray 102, with an inclined bottom having a lateral outlet 103 into a spout 104, which enters 35 the detergent tank 28, so that after use, the detergent is returned to the tank. Below the last section of the conveyor and above the wash water sump 101, is a wash water collecting tray 105, which collects wash water and delivers it back to the sump 101. Both the detergent 40 portion of the tank 28, and the wash water sump are heated by steam coils, 106 in the case of the former, and 107 in the case of the latter. Below the outlets from the drains 102 and 105, and above the liquid level in the tank 28 and sump 101, are strainers 108, 109. The 45 top of the tank is preferably covered in with chequer-plate, not shown in the drawing.

When drums like the drums 40 are laid on the cradles 31, the ends of the drums project at each side beyond the side frames 18, 19 as shown in Figure 3. It is important that the detergent liquid, which is hot and normally strongly alkaline, should only enter the drums and should not be sprayed about freely. If the operator failed to place any drum in position, when the empty cradle reached the nozzles 44, there would be a stream of detergent sprayed about unhinderedly. It is important, therefore, to stop the machine before this happens. To this end, a rail 110 supported on links 111, 112, is provided on the outside of the frame 19, and the link 112 carries a counter-balance weight 113, which tends to make the rail 110 rise. The link 111, carries a cam 114 to engage an electric switch 115. As long as the weight of the drums keeps the rail 110 depressed, the cam 114 will be out of engagement with the switch 115. In this condition, the switch 115 completes the control circuit for the motor 61, and 60 therefore, once the apparatus has been started, it will keep running. If the operator fails to load a drum, there is a sufficient gap between the two cradles on each side of the one unloaded, to permit the rail 110 to rise as the previously-loaded drum runs off it. The cam 114 will then swing into engagement with the switch 115, and break its circuit, and that of the driving motor 61, until the operator places a drum on the unloaded position, whereupon the apparatus will restart automatically.

Each of the shafts 74, 78 carries a cam 116, 117 respectively. The cams bear on spring plungers 118, 119,

and automatic valves 120, 121 in the pipe lines 97 and 83 respectively. These cams 116, 117 keep the valves 120, 121 closed when the frame 82 is lowered, so that the nozzles 44 are not inside the drums. They allow the valves to open as the nozzles rise and keep them open as long as they are inside the drums. The pumps 89, 98, being centrifugal pumps, can have their delivery cut-off in this way without difficulty.

In the use of this apparatus, the motor 61 being started and the pumps 89 and 98 in operation, with the tank 28 filled with hot detergent and the sump 101 with hot wash water, the machine is started by laying drums on the cradles of the conveyor as far as the washing position. The conveyor moves forward step by step, and at each step while the conveyor is at rest, the frame 82 is raised to bring the nozzles 44, and the wash water nozzle 120 up into the drums. As the nozzles rise into the drums, they spray the interior of each drum progressively with liquid, as indicated in Figure 9 at 121. The spray is arranged to extend radially outward from the nozzle and also upwards, but not downward, so that when the nozzle is at its uppermost position, the upper part of the drum has detergent liquid impinging at high speed upon it. This produces a stream of liquid which runs down the interior walls of the drum and runs out at the bottom around the exterior of the funnel 41, the stem 46 of this funnel being sufficiently smaller than the bung-hole to permit such cut-flow, and sufficiently high to ensure that the outlet is kept separate from the entering detergent, even when the nozzle 44 is lowered to the level of the funnel. As the nozzle 44 is lowered, the impinging jets 121, and detergent follow the descending stream of detergent and liquid down the walls of the drums and chase all the dirt out through the bung-hole. This is of great importance in ensuring clean drums, because both the alkaline action of the detergent, and the heat and physical disturbances caused by the impinging jet, are necessary to ensure complete cleansing. Each drum is entered in the construction shown by four nozzles 44 successively. Thereafter, it drains into the tray 102 at one of the stations 122 in Figure 1. Thereafter, hot wash water is delivered into it by the nozzle 120, and finally it drains at the three stations 123, 124 and 125. Being hot facilitates the draining process.

If it is important to conserve detergent, it is possible to have an additional hot water nozzle on the frame 82, in advance of the detergent nozzles 44, to help to carry out any easily removed material from the drum 46 before it is sprayed with detergent. If it is desirable to dry the drums after washing with water, an additional hot air nozzle may be incorporated and moved up and down with the frame 82 at one or more of the stations 123, 124, 125.

While the drum is at the initial station after it has been loaded and is still above the tray 52, any oil or other liquid which it contains has an opportunity to drain out into the tray 52 and collect in the tank 34. It is frequently surprising how much oil or other liquid can be collected in a day in this manner, and this economises detergent because the detergent does not become emulsified with so much oil or the like.

Referring now to the construction shown in Figures 4, 5, and 6, this is broadly similar to that shown in Figures 1 to 3, and similar parts are given similar reference numbers. The construction shown in these figures however, comprises two conveyors 11, side by side, which are supported on a frame-work consisting of uprights 130, 131, each of which run for the greater part of their length through tunnels formed of iron sheeting 132, 133, sub-divided by a central partition 134. This obviates any risk of damage in the event of the hereinbefore described safety devices failing to operate, and serves also to collect steam from the operations. The trays 102 are hung from the framework 130, 131, and have large lateral delivery extensions 135. These extensions 135

are coupled to the nozzles of the centrifugal pumps 136, which deliver by pipes 137 to a head-tank, not shown in the drawing. Similarly the draining tray 105 has an outlet 138 to a pump 139, delivering to another head-tank, not shown. In the head-tanks the liquids are allowed to settle or they may be subjected to a de-emulsification process, and the clarified liquor is delivered under pressure through other pumps to the frame 82 and the nozzles thereon.

The driving mechanism for the conveyors is housed in a casing 140 at the discharge end of the conveyor, and comprises an electric motor operating through a reduction gear 141, and a drive including a sprocket 142, a chain 143 and sprocket 144 to a shaft 145. The shaft 145 drives a longitudinal shaft 146, through bevel gears 147, and the shaft 146 is connected by further bevel gears 148, 149, with the crank shafts 74, 78, corresponding to the similarly numbered shafts of Figures 1-3. The drive of the conveyor sprocket 14, is taken through an interrupted gear to an intermittent shaft 150, and thence by a chain 151, to the sprocket 70.

The interrupted gear is shown in Figure 7, and comprises a gear 152 on the shaft 145, which has a section of teeth 153 standing out between a plain portion 154, which is concentric with the shaft 145, and is coincident with the pitch line of the teeth 153. The driven wheel 155 has four sections of teeth 156 adapted to mesh with the teeth 153 of the gear 152. The sections of teeth 156 are separated from one another by locking sections 157, which are curved so as to fit against the plain portion 154 of the gear 152. The gear 152 being driven in a direction indicated by the arrow A, when the teeth 153 come just past the position shown in the drawing, so that the first tooth 158 enters the hollow 159 in front of the teeth 156 and gear 155, the gear 155 will commence to be driven. The locking section 157 of the gear 155 will not prevent this because the shoulder 160 at the end of the plain portion 154 of gear 152, will have moved on towards the centre line between the centres of shafts 145, 150, and as the wheel 155 continues to turn, the shoulder 160 will reach a position so near to the centre line that the slight working clearance necessary between the two wheels will permit the movement to continue. The teeth 153, 156, meshing together will drive gear 155 through one quarter of a revolution, and then the locking portion 157 will engage the portion 154 of gear 152, and the gear 155 will be held from rotation while the shaft 145 makes three-quarters of a revolution. The conveyor is thereby driven intermittently, with periods of rest corresponding to three-quarters of a revolution of shaft 145, during which periods the frame 82 is raised and lowered. The advance of the conveyor takes place during the bottom quarter of the revolution of the cranks 80. In order to cushion the start and stop of the conveyor, a flexible coupling may be introduced between the gear 155 and the sprocket which drives the chain 151.

The operation is similar to that hereinbefore described.

I claim:

1. In apparatus for cleansing oil drums, the combination of a chain conveyor, disposed so as to have a substantially horizontal working path and a return path, a plurality of drum-cradles mounted upon said conveyor, a hollow bung-guide on each cradle projecting upwardly therefrom, said bung-guides being of such external diameter as to be capable of entering bung-holes of drums and centering the same on the cradle and being open toward the underside of the working path of the conveyor and spaced from one another at an even pitch-distance, means for moving the conveyor step by step through a distance equal to the aforesaid pitch-distance, a vertically-movable nozzle-frame beneath the conveyor, a series of nozzles mounted upon long nozzle pipes on the frame at a pitch-distance equal to the aforesaid pitch-distance so as to be in line with the bung-guides

when the conveyor is at rest, means for raising and lowering the nozzle-frame to pass the nozzles through the bung-guides, means interconnecting the step by step mechanism for advancing the conveyor with the means for raising and lowering the nozzle frame so that the advance movement of the conveyor takes place when the nozzle frame is lowered, means for supplying detergent liquid to the nozzles in the nozzle frame, a collecting tray beneath the conveyor and the nozzle frame for liquid, and a reservoir for detergent liquid connected to said tray to receive liquid therefrom and to deliver such liquid to the supply means to the nozzle.

2. Apparatus as claimed in claim 1, wherein the jets are so formed to direct liquid from them radially outwards from the jets on to the walls of the drums and the nozzle pipes are long enough to rise within the drums above the halfway line thereof so that the jet liquid impinges upon the walls of the drums at a progressively moving zone which covers by direct impingement the whole drum surface as the jet rises and falls.

3. A drum washer as claimed in claim 1, wherein the step by step feed mechanism of the chain is effected by a Geneva-cross mechanism.

4. Apparatus as claimed in claim 1, wherein the means for affording step by step movement to the conveyor comprises an interrupted gear.

5. Apparatus for cleansing oil drums as claimed in claim 1, wherein valve means are provided for cutting

off the flow of detergent to the nozzles in combination with means for operating said valve means comprising a ramp close to the path of the oil drums, means to urge the said ramp towards the oil drums, and connections from the ramp to the said valve means, whereby in the event of a break in the continuity of the line of oil drums on the conveyor, the detergent is cut off.

6. Apparatus as claimed in claim 1, wherein a casing is provided around the conveyor and oil drums over the portion of the travel of the conveyor where the nozzles enter the drums.

7. Apparatus as claimed in claim 1, wherein the bung-guides have funnel-shaped openings to the underside of the working path of the conveyor.

8. Apparatus as claimed in claim 2, wherein the jets deliver liquid throughout their entire up-and-down movement within the drums.
